ATTORNEY

UNITED STATES PATENT OFFICE.

JACOB HARE, OF CHICAGO, ILLINOIS.

METAL STORE FRONT.

Application filed November 4, 1925. Serial No. 66,805.

This invention relates to new and useful improvements in metal store fronts and more particularly to means adapted to be employed for supporting the panes of glass in position within the frame of the store front. The main object of my invention is the provision of a device of the above character which is extremely simple in construction and at the same time is so constructed as to eliminate necessary changes being made in the frame of the store front in order to fit the device thereto and thus eliminate time and labor in placing the device in position. Another object of the invention is the provision of a device of the above character wherein the same may be quickly and readily attached to the ordinary frame of the store front, window frame, or door frame, and is so constructed as to readily receive and clamp the edges of the glass for securely retaining the same in position.

With the above and other objects in view, my invention consists in the novel features of construction and the combination and arrangement of parts to be hereinafter more fully described, pointed out in the claims and shown in the accompanying drawings, in which:

Fig. 1 is a detailed perspective view illustrating the application of my device.

Fig. 2 is a front elevation.

Fig. 3 is a transverse section on the line 3—3 of Fig. 2.

Fig. 4 is a detailed section on the line 4—4 of Fig. 3, and

Fig. 5 is a detailed perspective view of one of the securing members.

Referring more particularly to the drawings, the numeral 1 indicates a portion of an ordinary frame used in the construction of store fronts, window frames and the like, and attached to the frame is my improved device which consists of the body plate 2 one edge of which lies flat against one surface of the frame 1 and is then bent outwardly at right angles to form back walls 3 with the upper edge of the back wall having a rounded beading 4 while the extremity of the body plate is first disposed in a parallel position with the body of the plate and thence at right angles to form an inwardly projecting flange 5.

The other edge of the plate extends downwardly over one edge of the frame and thence bent at right angles to form a securing flange 6 which embraces the face of the

frame 1 opposite the body portion of the strip.

The clamping plate 7 may be provided with various curvatures to form a fanciful design with one edge thereof bent inwardly to form a flange 8 which lies parallel and in abutting relation with the body of the plate 2. The securing member 7 is provided with reinforced members 9 which extend inwardly with their inner ends bent upwardly as shown in 10.

In order to secure the device to the frame 1 a fastening member 11 is provided the body of which is U shaped in form with one side thereof provided with a depending flange 12 which is adapted to lie flat against one face of the frame 1 as shown in Fig. 3 and secured thereto by means of a screw 13. This clamping member 11 has one side thereof projecting thru an opening 14 in the back wall of the body plate and the other wall lies parallel with and abuts the inner face of the flange 5 as shown in Fig. 3.

It will be noted that the fastening member 11 is provided with an offset portion 11' at one side thereof which fits within the opening 14 in the back wall of the body as clearly shown in Fig. 3 so as to permit the portions of the side of the member to lie flat against the inner and outer faces of the side walls of the flange 5 in order to securely brace the same and retain the same in its operative position. The inner wall of the securing member is provided with an internally threaded opening 15 adapted to receive the fastening bolts 16 which extend thru said openings 17 in the clamping plate 7. The bolts 16 are passed thru the openings 17 in the clamping plate 7 and engaged with the inner side walls of the securing members as shown in Fig. 3.

The upper portion of the gutter member is provided with a plurality of openings 18 and the front wall of the clamping member 7 is also provided with openings 19 to form air vents for the interior of the device.

Arranged within the gutter member are a plurality of blocks 20 used for forming rests for the inner edge of the glass 21. It will be apparent from the foregoing that the device may be quickly and readily placed in position by clamping one edge of the gutter plate over the one edge of the frame as shown in 1 and 3 and then simply placing the clamping members 11 in position so that the flange 12 may be readily connected to

one face of the frame. After this has been carried out, the clamping member 7 is arranged in position and the upturned ends of the arms 9 are positioned against the inner 5 face of one wall of the member 11 as shown in Fig. 3. The clamping member may be adjusted to a predetermined position and after the glass 21 has been placed in position, the bolts 16 are tightened to securely clamp 10 the glass. My device is extremely simple in construction, inexpensive to make and is of such nature as to permit the same to be quickly and readily installed on ordinary window frames when it is so desired without 15 the necessity of providing heel members as is usually the case to the present time.

While I have shown and described the preferred form of my invention, it will be obvious that various changes in the details 20 of construction and in the proportions may be resorted to for successfully carrying my invention into practice without sacrificing any of the novel features of construction or departing from the scope of the appended 25 claims.

Having thus described my invention, what I claim is:

1. A structure of the class described including a rectangular trough comprising a portion forming a back wall member and a 30 portion disposed to form a surface for a main frame, a member comprising a clamping plate adapted for engagement with said trough member, said members being spaced 35 apart so as to receive a window glass therebetween, and a member comprising a reinforcing portion adapted to maintain spaced relation between the lower extremities of the two described members thereby diverting 40 the clamping stress entirely to the upper extremities of said members, clamping means located at intervals and interposed through openings in the back wall of said first mentioned member and adapted for

bolting engagement with said clamping plate, said clamping means being provided with depending flanges having openings adapted for the insertion therethrough of screws whereby said clamping means may be secured to said main frame. 45

2. In a structure of the class described including two sash elements comprising a clamping means for intermediately disposed window glass, threaded clamp members to be inserted through openings in the back 50 wall of one of said members and registering with like openings in the opposite or front element whereby a bolt may be inserted for clamping and supporting the interposed glass, a spacing and reinforcing element 55 abutting the bottom surface of the back wall element and maintaining a fixed relation between the lower extremities thereof and diverting all of the clamping stress to the upper extremities, substantially as shown. 60

3. A device of the character described including a gutter member, a lateral wall integral therewith having openings there thru securing means having portions thereof extending through the openings, means for 70 attaching said securing means to a rigid support, a clamping plate and means adjustably connecting the clamping plate with the securing means.

4. A device of the character described 75 including a gutter member, a lateral wall integral therewith having openings there thru, securing means having portions thereof extending through the openings means for 80 attaching said securing means to a rigid support, a clamping plate and means adjustably connecting the clamping plate with the securing means, arms carried by the clamping member having their inner ends bent upwardly and engaged with a portion 85 of the securing means.

In testimony whereof I affix my signature.
JACOB HARE.
